UNITED STATES PATENT OFFICE.

HORATIO B. HOLLIFIELD, OF WASHINGTON, DISTRICT OF COLUMBIA.

PRACTICE APPARATUS FOR SMALL-ARMS.

1,094,854.

Specification of Letters Patent. Patented Apr. 28, 1914.

Application filed January 9, 1914. Serial No. 811,215.

To all whom it may concern:

Be it known that I, HORATIO B. HOLLIFIELD, a citizen of the United States, residing at Washington, in the District of Columbia, have invented certain new and useful Improvements in Practice Apparatus for Small-Arms, of which the following is a specification, reference being had therein to the accompanying drawing.

10 This application relates to practice apparatus for small arms and its general object is to eliminate certain objections developed in extensive practical use of such apparatus.

15 It is important to reduce cost while securing devices usable with regular service arms, which differ in construction, and equally adapted for convenient use in various kinds of practice, such, for example, as

20 testing rapidity of manipulation alone, or accuracy alone, or both together. With repeating pistols now being substituted in the United States service for arms of the revolver type, the devices heretofore furnished are not entirely satisfactory in the speed of the marking point, especially when the target is at or near the limit of distance to which the marker can be projected from the muzzle. The target heretofore used also

25 falls short of perfect convenience and adaptability for various kinds of practice. My devices while especially valuable for use with such pistols, is also adapted for use with other small arms.

30 In the accompanying drawings, Figure 1 is a partial, sectional, elevation of a pistol provided with my improved devices, the target being shown in edge view in front of the weapon. Fig. 2 is an axial horizontal section of a tube seen also in Fig. 1. Fig. 3 is a section on the line 3—3, Fig. 2. Fig. 4 is a view similar to Fig. 2, showing a modified construction of the same devices. Fig. 5 is a front view of a strip target and its holder.

35 Fig. 6 is a section on the line 6—6, Fig. 5.

In these views, A represents a repeating pistol having a barrel A' and a firing pin B which, except at the instant of impact in firing, is never in contact with the cartridge.

40 The latter is held in the usual chamber in the barrel, with its rear end in contact with

any suitable block C. The firing pin is normally held retracted by a light spring D which yields under the momentum imparted to the heavy pin by the impact of the 55 usual hammer E. The pistol itself, necessarily here shown in part, has no novelty whatever, but is a weapon now in common use.

My apparatus includes a tube F inserted 60 in the barrel of the pistol from the muzzle end thereof and preferably projecting to some distance from the muzzle while extending oppositely to the rear end of the cartridge chamber. In the axis of this tube 65 a rod F' is slidably mounted in bearings G, H fixed to the tube and itself fixed at its rear end to a sliding bearing block I which fits the interior of the tube and keeps this portion of the rod in the tube's axis. A 70 milled block J provided with a marking point J' is screwed upon the forward end of the rod in position to abut at its rear end the bearing block G. Between the blocks H and I is a light helical spring K normally urging the block J toward the block G. At its rear end the rod, or the block I fixed thereto, bears a projection L which extends rearwardly into the firing pin channel in the block B to meet the end of the 75 firing pin with which it is yieldingly held in contact by the spring K, when the parts are properly adjusted. From this arrangement, normally maintaining actual contact of the firing pin and rod, it follows that 80 when the hammer strikes the firing pin, practically its entire force is exerted in compressing the spring K and throwing the marking point forward with high velocity, nothing being lost by impact with the rod 85 or its projection L. The gain is large, since the rod and parts which move therewith are, and must necessarily be, heavy in order to give the momentum necessary for carrying the marker far beyond the point to which it 90 is positively pushed by the advancing firing pin. Obviously, inertia increases rapidly with the weight, and is in this case sufficient to neutralize a large part of the blow, were a blow given by the firing pin. In addition 100 to this highly important gain, there being no impact of the firing pin, there is no

necessity for providing and renewing from time to time a hardened steel member to receive such impact, as set forth in existing patents pertaining to this art. Moreover, 5 this construction obviates unequal wear of the meeting surfaces of the firing pin and rod and insures perfect alinement and an impulse that is always exactly axial.

The bearings G, H are provided with conical recesses about the rod so that while they have a long rigid bearing in the tube, the area of contact with the rod is very small, and while the rod is held in perfect alinement the friction is slight, even when the 10 rod has been laterally bent so as to give it, permanently, normal deflection. A further gain from this construction is found in the fact that when the rod is removed for any purpose it may be instantly reinserted, the 15 cones guiding its end and thus eliminating a very serious annoyance.

It is found that tubes exactly fitting the bore of one service pistol cannot be inserted in a second supposed to be of the same bore 20 and will not be frictionally held in a third because too small therefor. To obviate this difficulty, the tube is slotted or slit for a short distance on each side, as shown at N, 25 between small apertures N'. If the tube be small enough for use in the bore of least diameter, the slots may be wedged open to give the tube permanent set and increased 30 diameter at this point, so that the yielding enlargement adapts the tube to fit properly 35 in the larger bore. The apertures at the ends of the slot prevent splitting the tube in expanding it. The rear end portion of the tube is preferably provided with a slight angular or circumferential groove at O to 40 be yieldingly engaged by the usual shell-extracting nook O' with which all these arms are provided and under which the tube is forced in putting it in place. This gives, independent of thought or care, a further security against accidental slipping of 45 the tube after it is in place in the bore.

Instead of the fixed block H, I sometimes use a bearing H', Fig. 4, free from both tube and rod and so placed as to support the rod laterally at its middle or elsewhere. In this case, springs P, P' are used in both front and rear of the block, and the bearing is diminished centrally, as shown, so that it touches the tube only along annular surfaces 50 at its ends and thus has slight frictional resistance to movement. Evidently the combined length of the springs may be substantially equal to the entire distance between the terminal bearings, thus increasing the 55 excursion or projecting distance of the marker. It is obvious that I am not necessarily limited to one movable central block and two springs.

I use a strip target Q which bears in succession targets Q', Q'', etc., successively increasing in size to correspond with the apparent size of actual service targets placed at the different distances usually selected for practice, so that in accordance with the custom in the field, the marksman may fire a 65 given number of times at a distant target in miniature and may then slide the target strip to bring a larger target into place. In using strip targets, it is found that 70 grooves or fingers which have commonly 75 been used to hold and guide the strip soon fail to hold it with proper security, and I therefore provide a rubber block R having strip receiving passage R² extending through it from edge to edge, the block being cut away centrally as shown at R' to expose so much of the strip as must necessarily be visible, leaving the parts above and below the exposed portion concealed by portions S of the block. This gives all desirable 80 security, allows the strip to be pulled along in either direction, and adds nothing which can injure the marking point. By way of example, my devices have been shown and described as used with a repeating pistol, but obviously they are not restricted to use with that particular form of 85 small arms, but are adapted for use with various classes of weapons having greatly differing length of barrel as well as other 90 marked differences.

What I claim is:

1. In apparatus of the class described, the combination with a firearm having a firing pin movable rearwardly to some distance 100 from the cartridge chamber, of a marking rod located in the bore of the arm, bearing a marking point at its forward end and extending rearwardly into contact with the forward end of the firing pin, and a spring 105 normally maintaining such contact.

2. The combination with a firearm having in the rear of its cartridge chamber a block provided with a firing pin passage alining with the bore of the arm, of a firing pin normally held in said passage at some distance 110 from said chamber, a marking rod located in said bore and normally extending rearwardly into said passage and into contact with said firing pin, and a spring normally 115 maintaining such contact and yieldingly resisting the forward movement of the rod.

3. The combination with a firearm having alongside the rear portion of its bore a cartridge-extracting spring hook, of a marking rod tube, adapted to be inserted in said bore and pressed rearward alongside said hook, and provided near its rear end with an external circumferential groove in position to be engaged by said hook. 120

4. The combination with a marking rod 125

tube adapted to be inserted in the bore of a firearm, of a centrally perforated block fixed in the tube near its forward end, a marking rod sliding in the perforation in said block, a guiding block sliding in the tube near its rear end and fixed to the rod, a similarly perforated central block free from both rod and tube, and springs extend-

ing from the block last mentioned to the other blocks, respectively. 10

In testimony whereof I affix my signature in presence of two witnesses.

HORATIO B. HOLLIFIELD.
